GARMENT MATERIAL AND PATTERN

Alma D. Telzerow, New York, N. Y.

Application March 25, 1933. Serial No. 662,813

7 Claims. (Cl. 41—17)

This invention relates to garment material and a pattern and has for an object to provide an improved construction wherein the material and pattern coact so that repeats thereof may be provided on a long strip of fabric and then cut out and formed into a desired garment according to the particular pattern used.

Another object of the invention is to provide a strip of textile fabric of any desired length and any desired textile material, with a pattern printed thereon on one face of the fabric, and a design on the other face, the design being arranged to agree with the pattern.

A further object of the invention is to provide a garment material which is formed of a long strip of material having reoccurring uniform areas or sections, each area or section having on one face a dress pattern and on the other variously arranged ornamental motifs positioned to agree with the pattern at the back, so that when the pattern is cut out the various motifs will be made to appear in the correct position when the garment is completed.

An additional object is to provide a garment material formed of a long strip having reoccurring sections so formed that when cutting any section into parts as directed by the pattern on one face, the other face will present shaped pieces of cloth having ornamental motifs arranged in the proper places, so that when the cut pieces are arranged together as directed by the pattern a complete garment will be presented having the different motifs and body portion of the material arranged in the various desired places.

A still further object is to provide a garment material and pattern formed to coact with each other to secure from a minimum piece of cloth a proper fitting garment.

An additional object of the invention is to provide a piece of textile fabric having ornamentation thereon arranged with a body having motifs scattered thereover in a predetermined order and agreeing or coacting with the pattern of the garment adapted to be superposed thereon, whereby when the fabric is cut according to the pattern a complete cut-out garment is provided.

With the foregoing and other objects in view which will appear as the description proceeds, invention resides in the novel garment material and coacting pattern, and the process of forming garments as hereinafter more fully described and claimed, it being understood that any changes may be made within the scope of the claims without departing from the spirit of the invention.

In the accompanying drawings—

Figure 1 is a plan view of a roll or bolt of garment material disclosing an embodiment of the

invention, the bolt being partly unrolled with a portion cut therefrom;

Figure 2 is a rear view of the structure shown in Figure 1, except the cut-away portion;

Figure 3 is a top plan view of a roll of garment material disclosing a modified construction of the invention, part of the roll of material being spread out to better illustrate the areas of ornamentation;

Figure 4 is a plan view of a pattern sheet adapted to be placed on top of any of the areas of ornamentation on the roll shown in Figure 3.

Referring to the accompanying drawings by numerals, 1 indicates a bolt of garment material which may be of any desired fabric, for instance, cotton, silk, linen or other goods, and may be made in strips of any desired length. The strip forming bolt 1 is of a desired width to accommodate certain patterns as illustrated in Figure 2. It will be noted that the bolt 1 is printed on one face with various designs or motifs merging into each other, and these designs are arranged in reoccurring areas 2. Each area 2 is provided with auxiliary areas 3, 4, 5, 6, 7, 8 and 9. Areas 5 and 7 are substantially identical, while areas 6 and 8 are identical and areas 4 and 9 are identical. As illustrated in Figure 1, these areas near one edge are reversed from the opposite edge so that the pattern 10 printed on the back of the section 2 may outline properly the different parts of the garment with the various motifs correctly positioned when the garment has been completed. In the pattern 10 the skirt front 11 is arranged as shown in Fig. 2, so that the part 12 of the front 11 will have the auxiliary area 7 on the opposite face, while the portion 13 of the skirt back will have the area 5 on the back. By reason of this arrangement of the pattern with respect to the design, the design is caused to be properly positioned when the parts of the garment are assembled in proper order.

Naturally, the top portion 15 of the back 14, and the top portion 16 of the front 11 will be arranged together so that the motifs 5 and 7 will be arranged at the lower part of the skirt, and the motifs 6 and 3 will be arranged at the upper part of the skirt.

In section 4 the neck bands 17 and 18 will be found, while in the auxiliary area 3 the various members 19, 20, 21 and 22 will be found. It will be understood that the pattern 10 is printed on the back of each of the areas 2 in the order disclosed, and the front of each area is printed with the design as shown in Figure 1, so that when the pattern is cut out it may be arranged together in the usual manner of patterns and the various ornamental designs will be properly positioned as originally desired. By printing pattern 10 directly on the fabric on the reverse face, there can be no slippage of the pattern and any

one may readily follow the lines of the pattern when cutting is out.

As indicated in Figure 2, the skirt front, skirt back, blouse tie, neck band and blouse are all provided with lines for indicating the different sizes. It will thus be seen that if the person desires, the garment may be cut in any one of three sizes according to the way the pattern is marked. If the larger size is desired the cutter will naturally follow the outside line, and when the cutting operation is completed the garment will accordingly be accurately cut.

In ordinary commercial use the roll or bolt 1 is on the merchant's shelf, and a purchaser desiring some dress goods may have a bolt spread out disclosing one or more of the patterns 2. If desired a number of rolls of different designs may be displayed, and when a purchaser selects a particular design, two or more areas 2 may be cut 20 from the bolt according to the number of garments the purchaser desires. At home the purchaser may take two areas or more and turn the design face down so that the pattern is uppermost. The purchaser will then cut along 25 the lines as shown in Figure 2. The cut goods are then sewn together in the usual manner and the garment is complete.

In Figures 3 and 4 modified structures are shown which bring out the same inventive idea 30 but with an independent pattern sheet 22 on which a complete pattern may be arranged, or half a pattern as shown in the accompanying drawings. Where the pattern is arranged as shown in the drawings it is adapted to be applied 35 to the area 23 so that the various parts may be cut from the cloth. The same pattern or another pattern identical with it is used on the area 23' which is identical with area 23. This is merely a duplication in order to have the proper number of 40 pieces to make a proper fitting garment. The area 23 which is identical with area 23' is provided with a section 24 having substantially uniform designs throughout and arranged in connection therewith are special motifs, for instance, 45 motifs 25, 26, 27 and 28. These various motifs are arranged in a certain place and formed of certain shape so that when the pattern sheet 22 is placed on area 23 and the various pattern 50 members 29, 30, 31 and 32 are cut, the various motifs shown in Figure 3 will be correctly positioned on the various parts of the pattern sheets. For instance, the motif 25 will be at the large 55 end of the front portion of pattern sheet 29 and the motif 28 will be at the end of the back pattern sheet 30. The various pattern sheets may have a number of cutting lines as, for instance, lines 33, whereby different sized garments may be cut by the use of the same pattern. The particular pattern shown in the drawings is merely 60 incidental, as various patterns may be used but in every instance it is essential that the pattern sheet shall agree with the location of the motifs on the areas 23, whether one area or more are used to produce a single garment.

In both the preferred and modified forms the pattern sheets have been shown in connection 65 with a single area and on this single area one-half a garment is produced. The other half of the garment is produced from the next area 70 which is identical. Where different patterns are used the arrangement of the motifs must be changed accordingly, but in all the finished garments the motifs though of the same material will appear as if added material had been used 75 to produce the desired trimming effect.

I claim:—

1. A garment material composed of a strip of textile fabric bearing thereon or having incorporated therein successively reoccurring, grouped designs or ornamentations, and means forming a pattern on the back of the strip, the ornamentations on the face of the strip and the arrangement of the pattern on the back of the strip coacting in a manner to cause the ornamentations on the face of the strip to assume the correct positions in a completed garment. 80 85

2. A garment material comprising a strip of textile fabric formed of successive areas bearing groups of designs thereon arranged in predetermined order, and a garment pattern formed on the back of said strip and positioned to conform to the arrangement of the designs on the face of the strip so that when the strip is cut along the lines of the pattern, the different design members will be properly grouped as the garment is completed. 90 95

3. A garment material composed of a strip of textile fabric arranged with successive areas with designs, each area having a plurality of groups of designs arranged in a certain order with respect to each other, and lines on the rear face of the strip of fabric opposite each area of designs forming a pattern, the various parts of the pattern being arranged to agree with the arrangement of the designs on the face of the 100 fabric so that certain parts of the design will be arranged at the bottom of the garment and others at the top. 105

4. A garment material comprising a strip of textile fabric having markings on one face presenting a pattern, and design groups on the opposite face, said groups being duplicated on opposite sides of a central longitudinal line, with one group arranged in reverse order to the other 110 group. 115

5. A garment material composed of a strip of fabric having imprinted thereon a complete garment pattern on one face, and imprinted on the opposite face groups of design elements, said groups being arranged to coact with the various 120 parts of said pattern so that the various design elements will take predetermined positions on the finished garment. 125

6. A garment material composed of a piece of textile fabric bearing thereon various motifs near the respective ends thereof, said motifs being characteristic of the particular portion of the completed garment the motifs are to occupy and means forming a pattern on the back of said fabric, said means being positioned in 130 respect to said motifs so that the completed garment will have the motifs positioned thereon in a predetermined order. 135

7. A garment material composed of a strip of textile fabric having successive areas bearing body ornamentation and a plurality of motifs arranged in prescribed order at different places over the areas, said motifs being characteristic of the particular portion of the completed garment said motifs are to occupy, and means presenting a pattern structure on the rear of said fabric, said pattern structure being so positioned that said motifs will occupy the position intended in the completed garment when the fabric is cut along the pattern structure, said pattern structure including lines indicating a plurality of sizes. 140 145
